UNITED STATES PATENT OFFICE.

ALFRED C. NEWMAN, OF FARGO, NORTH DAKOTA,

ATTACHMENT FOR PENCILS AND PENHOLDERS.

1,230,761.

Specification of Letters Patent. Patented June 19, 1917.

Application filed November 24, 1916. Serial No. 133,248.

To all whom it may concern:

Be it known that I, ALFRED C. NEWMAN, a citizen of the United States, and a resident of Fargo, in the county of Cass and 5 State of North Dakota, have invented a new and Improved Attachment for Pencils and Penholders, of which the following is a full, clear, and exact description.

My invention relates to a tubular device 10 adapted to be slipped onto a lead pencil or a penholder and having a strip to be unwound or to be wound thereon. My invention is particularly adapted for embodiment in a variable calendar although not limited 15 in all its phases to such use, since the strip may be utilized for other purposes as for bearing advertisements or for making memoranda for example.

Objects of the invention are to provide 20 an attachment of the indicated character, adapted to be moved on the pencil or penholder to the front thereof and retained in position for the purpose of protecting the point as well as preventing the point from 25 puncturing the pocket of the user, while at the same time the preponderance of weight thus given to the lower end of the pencil or penholder, and the increased diameter given to said lower end by reason of the attachment, will serve to retain the pencil or penholder in the pocket.

Further objects are to provide effective friction between the interior of the attachment and the pencil or penholder, and to 35 provide for effectively gripping the inner end of the strip.

Other objects, and the advantages of my improved device, will appear as the description proceeds.

40 Reference is to be had to the accompanying drawings forming a part of this specification in which similar reference characters indicate corresponding parts in all the views.

45 Figure 1 is a side elevation of my improved attachment showing the same applied to a lead pencil;

Fig. 2 is an enlarged vertical section of the attachment on the line 2—2, Fig. 1;

50 Fig. 3 is a horizontal section on the line 3—3, Fig. 2;

Fig. 4 is a view similar to Fig. 2 but illustrating a modification;

55 Fig. 5 is a horizontal section on the line 5—5, Fig. 4.

Referring more particularly to the form

of the device shown in Figs. 1 to 3, the same includes an inner split sleeve 10 adapted to fit onto a lead pencil A or a pen holder. The sleeve 10 is preferably slightly flaring 60 at both ends as indicated at 11 to facilitate the placing of the same on the pencil or the like, the flaring or flanged ends 11 serving also to retain in position an outer shell 12, the said sleeve and shell being relatively 65 turnable.

Wound upon the sleeve 10 between the same and the shell 12 is a flexible strip 14 of paper or fabric. The inner end of the strip 14 is clamped by passing the same 70 through the longitudinal opening 13 presented between the opposed edges of the split sleeve 10. The strip is thus effectively held at its inner end so that the strip may be unwound by a pull on the free outer end 75 thereof or wound up by a relative turning of the sleeve and shell.

The shell 12 is formed with a wide opening 15 to expose the strip 14 for the major portion of said shell and there is formed in 80 the shell between the ends of the opening 15 adjacent parallel slots 16, 17, so that the end of the strip 14 may be passed outwardly through the one slot 16 and then over the intermediate bar 18 produced by 85 said slots and then inwardly through the slot 17, the end finally passing outwardly again through the adjacent side of the opening 15 that the said end may be conveniently grasped. The provision of the slots 16, 17 90 with the intermediate bar 18 and the side bars 18^a, 18^b produced by said slots and by the opening 15 serves to exert friction on the outer end of the strip to prevent too free a movement of the strip or of the relatively 95 rotating elements of the device.

In the illustrated example, the invention is embodied in a calendar. For this purpose the initials of the days are produced in vertical sequence on the exterior of the 100 shell 12 on both outer bars 18^a, 18^b. The initials of the days run in reverse directions on the respective bars 18^a, 18^b of the shell 12 so that the said letters may be read relatively to the matter on the strip 14 regardless of whether the said strip is inserted in either direction, that is to say, from left to right or right to left in passing it through the respective slots 16, 17. Co-acting with the initials of the days of the 110 week on the shell, calendar matter is produced on the strip 14, there being produced

vertically the month and year adjacent to the end thereof. Inward from the month and year the days of the month are produced in horizontal and vertical rows after the manner of many calendars so that the horizontal rows, such as 7, 14, 21, 28 of the days of the month will aline with a particular day of the week. It is to be understood that the days and the month and year will be duplicated on the strip for the several months so that a portion may be torn off and another portion brought into proper relation to the initials of the days of the week. The split sleeve 10 provides an effective friction on the pencil or penholder in addition to forming the means for clamping the inner end of the strip 14, in the form above described.

As indicated in dotted lines in Fig. 1, the attachment may be moved to the front end of the pencil to protect the pencil point and prevent the same from puncturing the pocket. At the same time it will be clear that the material increase of the weight at the pointed end of the pencil will tend to retain the pencil in the pocket when inserted point downward and in addition the increased diameter will, by giving a better engagement with the walls of the pocket, assist in retaining the pencil in the pocket.

In the form shown in Figs. 4 and 5, the inner split sleeve 10 and the outer shell 12, as well as the strip 14, are the same as in the first described construction. In addition to the described elements, however, a second split sleeve 19 fits friction-tight on the inner sleeve 10 and the inner end of the strip 14 is passed through the longitudinal opening or slot presented by the opposed ends of said sleeve 19, the strip being thus held between the two sleeves 10 and 19.

It is to be understood that the rows of the initial letters representing the days of the week may be produced by any suitable method, such as printing, stamping, etc.

Having thus described my invention, I claim as new, and desire to secure by Letters Patent:

1. An attachment of the class described including an inner split sleeve to slidably receive a pencil or penholder and frictionally engage the same for retaining the attachment in position, an outer shell turnable on the said sleeve and spaced therefrom, and a strip between the said sleeve and shell adapted to be wound or unwound, the said shell having an opening to expose the strip and having a pair of parallel longitudinal slots between the ends of said opening, the shell furthermore having longitudinal bars separating the opening from the respective slots and a third longitudinal bar between the slots, the said strip having

its outer end extending through the slots over the intermediate bar and under the other mentioned bars.

2. An attachment of the class described including an inner split sleeve to slidably receive a pencil or penholder and frictionally engage the same for retaining the attachment in position, an outer shell turnable on the said sleeve and spaced therefrom, and a strip between the said sleeve and shell adapted to be wound or unwound, the said sleeve having an opening to expose the strip, the shell furthermore having means between the ends of said opening frictionally holding the outer end of the said strip.

3. An attachment of the class described including an inner split sleeve to slidably receive a pencil or penholder and frictionally engage the same for retaining the attachment in position, an outer shell turnable on the said sleeve and spaced therefrom, a strip between the said sleeve and shell adapted to be wound or unwound, the said shell having an opening to expose the strip, the shell furthermore having means between the ends of said opening frictionally holding the outer end of the said strip, and a second split sleeve fitting on and frictionally engaging the first sleeve, the inner end of the said strip extending through the split of the second sleeve and being clamped between the two sleeves.

4. A calendar attachment of the class described, including an inner sleeve to slidably receive a pencil or penholder and frictionally engage the same, an outer shell turnable relatively to the said sleeve and spaced therefrom, to accommodate a wound strip, a strip in said space and adapted to be unwound or wound, means on the shell to frictionally hold the outer convolution of the strip, the said strip bearing thereon series of numerals representing the days of the calendar months in rows, and said shell bearing indicia of the days of the week in separate rows in reversed order.

5. A calendar attachment of the class described, including an inner sleeve to slidably receive a pencil or penholder and frictionally engage the same, an outer shell turnable relatively to the said sleeve and spaced therefrom to accommodate a wound strip, and a strip in said space and adapted to be unwound or wound, said shell having vertical slots and vertical bars separated by the said slots, said strip bearing thereon the days of the calendar months in rows, the numerals in vertical rows running in arithmetical order, and two of the said bars of the said shell bearing thereon in reversed order separate indicia representing the days of the week.

ALFRED C. NEWMAN.
